US0D1027444S

(12) United States Design Patent (10) Patent No.: US D1,027,444 S
(45) Date of Patent: * May 21, 2024

(54) STORAGE CASE

(71) Applicant: HTC Corporation, Taoyuan (TW)

(72) Inventors: Wei-Ting Hsiao, Taoyuan (TW);
Yien-Chun Kuo, Taoyuan (TW)

(73) Assignee: HTC CORPORATION, Taoyuan (TW)

() Term: 15 Years

(21) Appl. No.: 29/813,743

(22) Filed: Nov. 1, 2021

(51) LOC (14) Cl. 03-01

(52) U.S. Cl.

USPC D3/294; D13/108

(58) Field of Classification Search

(57) CLAIM

The ornamental design for a storage case, as shown and described.

DESCRIPTION

FIG. 1 is a perspective view of a storage case showing the new design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view thereof.

The broken lines depict portions of the storage case. The broken lines form no part of the claimed design.

1 Claim, 7 Drawing Sheets
